[57] CLAIM

The ornamental design for a bug repellent device, as shown and described.

DESCRIPTION

FIG. 1 is a perspective view of a bug repellent device showing my new design;

FIG. 2 is an enlarged perspective view thereof, shown without the environmental structure;

FIG. 3 is an enlarged right side elevational view thereof, the opposite side being a mirror image;

FIG. 4 is an enlarged front elevational view thereof, the rear view being a mirror image;

FIG. 5 is an enlarged top plan view thereof; and,
FIG. 6 is an enlarged bottom plan view thereof.

The broken line illustration of the hat in FIG. 1 shows environmental structure and forms no part of the claimed invention.
